United States Patent Office

Des. 229,256

Patented Nov. 20, 1973

229,256

SOFA

Stapleton Long, 1629 Christmas Drive,
Morristown, Tenn. 37814

Filed May 3, 1972, Ser. No. 250,114

Term of patent 3½ years

Int. Cl. D6—02

U.S. Cl. D6—63

FIG. 2

FIG. 1 is a view, in front elevation, of a sofa showing my design; and

FIG. 2 is a view, in side perspective, thereof.

The sofa back is plain and conventional throughout and the side not shown is identical to that shown.

I claim:

The ornamental design for a sofa, as shown and described.
